UNITED STATES PATENT OFFICE.

HARRY S. STORMER, OF JOHNSTOWN, PENNSYLVANIA.

TUBE AND FLUE CLEANER.

No. 874,258.

Specification of Letters Patent.

Patented Dec. 17, 1907.

Application filed January 12, 1907. Serial No. 352,039.

To all whom it may concern:

Be it known that I, HARRY S. STORMER, a citizen of the United States, residing at Johnstown, in the county of Cambria and State of Pennsylvania, have invented new and useful Improvements in Tube and Flue Cleaners, of which the following is a specification.

This invention relates to boiler tube and flue cleaners, and more particularly to that class of cleaners comprising a rotary motor which is operated by a turbine wheel actuated by a suitable pressure medium fed through a hollow tube or pipe which is connected to the cleaner and serves as the handle for manipulating the cleaner while in operation.

The cleaner of the present invention includes a head which is rotatable and associated with the remaining mechanism by a ball and socket joint and operates by a pounding action as well as penetration to loosen and remove scale or other material adhering to the interior of a tube or flue, the several parts of the mechanism being so assembled that a compact construction will result and the head permitted to assume an angular position relatively to the body of the cleaner for adapting the latter to be operated in tubes or flues having comparatively sharp or abrupt curves or bends.

The invention consists in the novel combination of elements as a whole and in detail more fully hereinafter referred to.

In the drawings, Figure 1 is a perspective view of a cleaner embodying the features of the invention. Fig. 2 is a longitudinal vertical section thereof shown applied. Fig. 3 is a front end elevation of the same. Fig. 4 is a rear end elevation of the diaphragm and casing. Figs. 5 and 6 are side elevations partially in section of portions of the motor. Figs. 7, 8 and 9 are detail views showing the cleaning head and portions of its connections. Figs. 10 and 11 are detail views of other parts of the cleaner.

Similar characters of reference are employed to indicate corresponding parts in the views.

The numeral 1 designates a flared coupling cap having a reduced extremity 2 formed with wrench engaging faces and in which is secured the end of a pipe or tube 3, said pipe or tube serving as a conduit means and also as a handle, as will be more fully hereinafter

specified. The coupling cap 1 has its front extremity secured in the rear portion of a surrounding shell or casing 4. Within the shell or casing 4 is a diaphragm or partition 5, the coupling cap 1 and diaphragm 5 being removably connected to the said shell or casing. The diaphragm 5 has a central interiorly screw-threaded hub 6 with a collar seat 7 at the forward extremity thereof or in the center of the face of the diaphragm.

Adjacent to the periphery of the diaphragm 5 is a plurality of feed bores or openings 8, extending diagonally therethrough, and secured in the hub 6 is a screw-threaded shaft 9, having an intermediate collar 10, which fits in the seat 7, the shaft 9 projecting forwardly from the diaphragm and screw-threaded throughout its full length, except at the point where the collar is located. A pin 6^a is also used as an additional securing means for the hub 6 on the shaft 9. The front extremity of the shaft 9 is longitudinally recessed or grooved, as at 11. Rotatably mounted within the shell or casing 4, and movable around the shaft 9, is a motor member or element comprising a body 12, having a cup recess 13 at the center of the rear side and communicating with a bore 14, which is considerably greater in diameter than the diameter of the shaft 9.

Within the cup recess 13 a ball cup 15 is secured, and on the shaft 9 adjacent to this cup is a cone 16, a plurality of balls 17 being held between the inclined surface of the cone and the cup, as clearly shown by Fig. 2, to ease the movement of the motor member or element and reduce the friction thereon to a minimum. The body 12 of the motor member or element has a diagonally reduced tubular extension 18 projecting forwardly from the center thereof, the bore 14 opening into the said extension and the latter provided with interior screw-threads, as at 19. A cup recess 20 is also formed in the central portion of the fore-part of the body 12 and the adjacent portion of the extension 18 to receive a cup 21 in a position reverse to the cup 15, and on the adjacent part of the shaft 9 is a cone 22 also in a position reverse to the cone 16, and between the cone 22 and cup 21 a plurality of balls 23 are mounted. The cup 21, cone 22, and balls 23 provide an anti-frictional bearing between the shaft and the extension 18, and by employing the dual antifrictional elements just explained regu-

larity and ease of movement of the motor element or member is insured, as well as the parts coöperating therewith, and which will be presently explained. The cones 16 and 5 22 are interiorly screw threaded and readily applicable to and removable from the shaft 9, and no part of the motor element or member is permitted to contact with or bear upon the shaft.

- 10 The reverse positions of the cones 16 and 22 and the cups 15 and 21, together with the balls 17 and 23, take up wear on the anti-frictional elements, and thereby sustain the motor element or member in accurate running position, and also provide a sensitive 15 operation thereof. The cone 22 has its front enlarged extremity provided with diametric slots 22^a to receive a wrench or spanner, and also a seat 24 in which is fitted a locking 20 washer 25, having an opening 26 therethrough of such diameter as to fit over the end of the shaft, and a locking projection 27 to engage the recess or groove 11, as clearly 25 shown by Fig. 11. This locking washer is held in the seat 24 by a nut 28 applied to the screw-threaded forward end of the shaft 9, and said washer operates to prevent loosening of the cone 22 due to the rotation of the antifrictional devices engaging therewith, 30 and thereby preserves the desired association or relation between the said cone 22, the cup 21 and the balls 23.

The body 12 of the motor member or element is free to rotate within the shell or casing 4 and has its rear face located close to the front face of the diaphragm 5; and adjacent to the periphery thereof a plurality of openings 29 is formed therethrough at regular intervals, and diagonally disposed in planes at 40 right angles to the bores or openings 8 of the diaphragm. From the foregoing it will be seen that the element or member, including the body 12 and the extension 18, is in the form of a wheel with the openings or ports 45 therein of the same diameter as the openings 8 in the diaphragm, the latter forming a base and preferably constructed of bronze to render the same strong and durable.

Removably disposed in the front extremity of the extension 18 is a socket 30, having 50 a forwardly flared opening 31 in its front end. Within the socket is a hemispherical member 32 of the cleaner head shank or stem 33 is loosely mounted, and has a slot 34 cut 55 diagonally through the rear portion thereof to receive a limiting pin 35, secured in the socket and operating to prevent the member from moving rearwardly beyond a predetermined distance, and also from turning in the 60 socket, the slot 34 being of such width as to obviate any tendency of the pin to restrict the movement of the shank or stem 33. The shank or stem 33 at an intermediate point is provided with a stop-collar 34^a, and adjacent 65 to the said collar is a square portion 35^a.

The terminal of the shank or stem in advance of the square portion is screw-threaded, as at 36. On the stem or shank 33 a head or knocker 37 is mounted, and has a bore 38 through the center thereof to adapt 70 the same to be readily slipped over the free extremity of the said stem or shank, the rear part of the bore 38 being of the same contour as the portion 35 of the stem and the remaining portion of the bore being of greater 75 diameter than the stem and terminating in a front enlargement or socket 39^a. By this means the head or knocker 37 is held against rotation on the part of the stem or shank which it engages, and is secured in applied 80 position by means of a flanged nut 39 fitted over the screw threaded terminal 36 of the stem or shank, and having a reduced portion 40 projecting into the socket 39^a. This nut 39, after being applied, is held against movement by a cotter pin 41 inserted through the terminal 36 of the stem or shank against the outer or head portion of the nut 39. The head or knocker 37, as shown, has a quadrangular pyramidal contour with concave 90 faces 42, which provide cutting edges 43. The form of the head or knocker, however, may be varied, it only being essential in the construction of the same to have it equipped with cutting edges. The reduced extremity 95 40 of the nut 39 frictionally engages the socket 39^a. The head or knocker 37 may be readily separated from the stem or shank 33 and heads of different forms may be applied to the stem or shank as found necessary or 100 desirable.

The flared coupling cap 1 forms in rear of the diaphragm 5 a chamber 44 which receives the motive medium from the conduit 3, the latter serving as a handle to direct the longitudinal movement of the cleaner as a whole through a tube or flue, and said conduit may be as long as desired and composed of any number of coupled sections.

Any motive fluid may be used, such as air 110 or steam, which is admitted through the conduit 3 into the chamber 44, and from the latter passes through the openings 8 in the diaphragm 5, through the ports or openings 29 in the body 12 of the motor member or wheel. 115 Owing to the fact that the ports or openings 29 are disposed in planes at right angles to the openings 8 and are diagonally arranged in the body 12, the latter is rotated, the air or steam exhausting in advance of the cleaner, 120 and to some extent assisting in the cleaning operation by blowing the loose material ahead and clearing the way for a more expeditious progress of the cleaner. The rotation of the motor member or wheel causes a 125 similar movement of the socket 30, and such actuation of the latter imparts a rotary movement to the stem or shank 33 and the head or knocker 37 by means of the pin 35 engaging the hemispherical member 32 on 130

the said stem or shank. As the stem or shank 33 and the head 37 rotate they simultaneously and unitedly change their angular position with respect to the remaining portion of the cleaner, and the head or knocker is brought into contact with the scale or sediment within the tube or flue with considerable force at the same time that the said head is rotated. This operation of the head 10 will expeditiously loosen the scale or sediment, and as the head is continually changing angular position the interior portion of the flue or tube will be fully engaged.

One of the main advantages of the improved cleaner is economy in the use of the motive medium which is due to the uniformity of diameters of the openings 8 and the ports or openings 29. Another effective feature is the disposition of the ports or openings 29 in diagonal relation in the body 12, and in planes at right angles to the openings 8. Structurally, a further advantage of the improved cleaner resides in having the pin 35 stationary in the socket 30, the said pin under this condition holding the hemispherical member or ball 32 in one position against the front of the socket, and thereby keeping the dust and dirt from working back to the anti-frictional bearing immediately in rear of the socket. A further structural advantage is in having the head or knocker 37 of materially less diameter than the interior of the flue or tube to be cleaned, and imparting to the said head or knocker not only a rotary movement, but also a pounding action, or causing it to bound regularly from one position to another with respect to the interior of the tube or flue, and thus break the scale or sediment in pieces, instead of grinding it. Another structural advantage is the attachment of the socket 30 in the extension by screw threads, in view of the fact that cleaners of this type are subject to considerable vibration, and the parts at the forward extremity of the cleaner will, under the structural relation specified, be prevented from working loose, and furthermore, though the pin will wear the hemispherical head 32 and become loose, it cannot fall out or be accidentally displaced.

The parts of the improved cleaner may be readily separated and assembled, and should any of the same become materially worn after extended use they can be replaced at a minimum cost without dispensing with the remaining portions of the cleaner.

It will also be understood that changes in the proportions, dimensions and minor details may be resorted to without departing 60 from the spirit of the invention.

Having thus fully described the invention, what is claimed as new, is:

1. A tube or flue cleaner comprising a casing, a fixed diaphragm in the casing provided with openings therethrough near the

periphery, a stationary shaft secured to the diaphragm and projecting forwardly from the latter, a rotary motor element located close to the diaphragm and movable around the shaft, the rotary motor element also having openings therethrough near the periphery coinciding with those of the diaphragm and provided with an extension which projects beyond the end of the shaft, and a single cleaning head having a shank loosely and 70 separably connected to the forward end of the extension in advance of the end of the shaft, the said cleaning head and shank having lateral movement in opposite directions in addition to the rotative movement imparted thereto by the motor element. 75

2. A tube or flue cleaner comprising a casing, a fixed diaphragm in the casing, a fixed shaft held by and projecting inwardly from the diaphragm, a rotary motor element 80 loosely operating around the shaft and provided with a forwardly projecting rigid extension, antifrictional devices interposed between the shaft and the rotary motor element, and a single cleaning head having a shank loosely and 85 separably connected to and within the forward end of the extension in advance of the shaft, the cleaning head and its shank having movement in opposite lateral directions in addition to the rotative movement imparted thereto by the rotary 90 motor element. 95

3. A tube or flue cleaner comprising a fixed diaphragm, a fixed shaft screw threaded from end to end and held by the diaphragm, 100 a rotary motor element surrounding the shaft in advance of the diaphragm and provided with a tubular extension and having ball cups disposed therein in reverse positions, screw threaded cones engaging the 105 shaft and also reversely positioned, balls interposed between the cones and the cups, the rotary motor element being unconnected to the shaft except by the cups, cones and balls, and a cleaning head movably and 110 separably secured in the forward extremity of the extension of the rotary motor element in advance of and in alinement with the said shaft.

4. A tube or flue cleaner comprising a fixed shaft, a rotary motor element disposed on 115 the shaft and provided with a forwardly projecting tubular extension terminating in advance of the end of the shaft, cones arranged in reverse positions on the shaft, cups carried by the rotary motor element and also disposed in reverse positions, balls between the cups and cones, the forward cone having a seat, a locking washer fitted in the seat of the forward cone and having an inner projection engaging a portion of the shaft, a locking nut 120 engaged with the shaft and bearing against the washer, a socket removably mounted in the free end of the extension, and a cleaning head movably secured in the said socket. 125

5. A tube or flue cleaner comprising a rotary 130

motor element having a tubular extension, a shaft around which the said element operates, a tubular socket secured in the forward extremity of the extension and having an opening therethrough, a stem or shank provided with a rear hemispherical member fitted in the socket, the said head having a rear diametrically arranged slot therein, a pin extending across the socket and loosely engaging in the slot in the member, and a cleaning head mounted on the free extremity of the stem or shank.

6. A tube or flue cleaner comprising a casing, a rotary motor element mounted in the casing, a fixed shaft around which the motor element operates, the motor element having a tubular extension projecting forwardly therefrom, a stem or shank carrying a cleaning head and also provided with a rear hemispherical member, a socket mounted in the extension and engaged by the hemispherical member, and means carried by the socket for engaging the rear portion of the hemispherical member to prevent the latter from hav-

ing rearward movement, the hemispherical member with the socket providing a dust and dirt excluding means.

7. A tube or flue cleaner comprising a casing, a rotary motor element in the casing, a stem or shank movably connected to a portion of the rotary motor element and having an intermediate stop collar, an adjacent angular portion, and a screw-threaded free extremity, a cleaning head fitted over the screw threaded extremity and engaging the angular portion to prevent the head from rotating on the stem or shank, a flanged nut engaging the screw-threaded extremity of the shank and having a portion thereof fitted in the adjacent end of the head, and means for securing the nut against movement.

In testimony whereof I have hereunto set my hand in presence of two subscribing witnesses.

HARRY S. STORMER.
